RECEIVER SELECTIVITY CONTROL CIRCUIT

Garrard Mountjoy, Bayside, N. Y., assignor to
Radio Corporation of America, a corporation
of Delaware

Application March 12, 1937, Serial No. 130,458

7 Claims. (Cl. 178—44)

My present invention relates to selectivity control circuits for radio receivers, and more particularly to a novel method of, and means for, controlling the selectivity of the preselector circuits of a receiver.

Band width control devices, or fidelity adjustment means, are well known in the art of radio reception; such devices are generally employed to increase the radio frequency selectivity of a receiver, and decrease the fidelity of signal reproduction, when distant, or weak stations are received. Conversely, the band width control device is generally used to decrease the selectivity, and thus increase the fidelity of signal reproduction, when strong, or local, stations are received. The fidelity control device has generally been located in a signal selection circuit, and adjustment of the control device results in a variation of the resonance curve characteristic of the selection circuit. Obviously, a fidelity control device should have a minimum number of elements, and function in a reliable manner to regulate the selectivity of the receiver.

Accordingly, it may be stated that it is one of the primary objects of my present invention to provide a selectivity control device which is constructed of a minimum number of elements and acts during one portion of its adjustment to maintain the receiver preselector circuits tuned to a common carrier frequency and hence imparts desirable selectivity to the receiver; and during another portion of its adjustment it functions oppositely to detune at least two cascaded pre-selector circuits from the common carrier frequency with the result that a broadened overall resonance curve characteristic is obtained for the pre-selector circuits.

Another important object of the invention may be stated to reside in the provision of a selectivity control device for the cascaded tunable radio frequency circuits of a receiver, wherein the control device comprises an inductive reactance electrically associated with the inductive reactance of each one of the cascaded radio frequency circuits, and a single switch device being employed for rendering either one of the inductive reactances effective as a short-circuiting inductance with respect to its associated radio frequency circuit.

Yet another object of the invention may be stated to reside in the provision of a selectivity control device which is essentially utilized to control the overall resonance curve characteristic of the tunable radio frequency circuits of a superheterodyne receiver, while an auxiliary band

width control device is employed to regulate the resonance curve characteristic of the IF network, and the two control devices being mechanically coupled in such a manner that the radio frequency circuits of the receiver are broadened at a predetermined angle of adjustment of the control device for the IF network.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect.

In the drawing:

Fig. 1 is a schematic circuit diagram of a superheterodyne receiver embodying the invention, and

Fig. 2 graphically represents the electrical operation of the selectivity control device for the pre-selector circuits.

Referring now to the circuit diagram shown in Fig. 1, it is first pointed out that the receiver shown therein is of the superheterodyne type. It is to be clearly understood that the receiver can be of the tuned radio frequency type insofar as the construction and function of the pre-selector selectivity control device are concerned. The receiver comprises the usual signal collector A, and the latter may be a grounded antenna circuit, a loop antenna, a radio frequency distribution line or a capacitive antenna device of the type usually employed on mobile vehicles, such as automobiles. The radio frequency amplifier 1, which may have one or more tubes, is shown as being provided with a tunable radio frequency input circuit 2. The input circuit 2 comprises an inductance coil 3 and a variable tuning condenser 4. The output energy of the radio frequency amplifier 1 is transmitted to the tunable input circuit 5 of the converter network 6. The circuit 5 comprises the inductance coil 7 and the variable tuning condenser 8.

To preserve simplicity of disclosure the converter network has been shown as of the combined local oscillator-first detector type, and in this case a tube of the 6A7, or 2A7 type, may be employed in the circuit. The numeral 9 denotes the tunable local oscillator tank circuit of the converter, and the reference numeral 10 denotes the usual mechanical uni-control device which functions simultaneously to vary the rotors of

the variable condensers used in the signal circuits and the local oscillator tank circuit. Those skilled in the art are fully aware of the fact that the frequency range of the tank circuit 9 will differ from the common frequency range of signal circuits 2 and 5 by a frequency value which is equal to the operating IF. If the receiver is of the broadcast type, which means that the signal frequency range is from 500 to 1500 kc., then the IF may have a value chosen from a range of 175 to 465 kc. The resonant output circuit 11 of the converter 6 is fixedly tuned to the operating IF, and it is coupled to a following resonant circuit 12 which is also tuned to the IF. One or more stages of IF amplification may follow the IF network 11-12, and the usual second detector and audio amplifier circuit, terminated by a reproducer, will be included in the receiver.

It will be understood by those skilled in the art that the receiving circuit shown in Fig. 1, and described up to this point, is of a conventional type. Many variations in construction of the receiver are possible. For example, the radio frequency amplifier may comprise several tunable amplifiers in cascade, and the converter network may employ separate first detector and local oscillator tubes. The tuning mechanism 10 denoted as "Tuner," in Fig. 1, is manually adjusted so that the desired stations may be received. The degree of coupling between IF circuits 11 and 12 may be manually adjusted in any desired manner, and the numeral 13 designates in conventional manner a band width control device which may be provided in the IF network to adjust the band width. It will be obvious to those skilled in the art that the adjustment of the degree of coupling between circuits 11 and 12 will result in varying the resonance curve characteristic of the IF network from a single-peak curve to a wide, double-peak curve.

The single-peak curve, secured by coupling between circuits 11 and 12 which is critical or less than critical coupling, is employed when receiving weak, or distant, stations. By increasing the degree of coupling between circuits 11 and 12 to more than critical coupling the resonance curve characteristic is broadened and may even have a double peak. As stated heretofore, band width control devices are well known and are usually provided to control the fidelity of signal reproduction of a receiver. At wide-band adjustment of device 13 practically all the modulation side bands are transmitted to the second detector. On the contrary when device 13 is adjusted to its high selectivity adjustment, then many of the higher audio frequencies are prevented from reaching the second detector.

It is often desirable, in order to insure efficient and satisfactory signal reproduction under different conditions of signal reception, to provide control of the selectivity of the radio frequency pre-selector circuits of the receiver. Considering the pre-selector circuits 2 and 5 in Fig. 1, there is shown a simple and highly effective arrangement for controlling the receiver selectivity. The coil 14 is physically positioned adjacent coil 3 so as to secure reactive coupling between the two coils. A similar coil 15 is positioned adjacent coil 7 so that the latter two coils are reactively coupled. A manually adjustable metallic contactor 16 is provided for slidable contact with a pair of metallic contacts 17 and 18. The contactor 16 is grounded, and one of the contacts

17 is connected by lead 19 to one terminal of coil 14, whereas the opposite terminal of the coil is grounded. The contact 18 is connected by lead 20 to one terminal of coil 15 and the opposite terminal of the coil is at ground potential. It will be noted that the contacts 17 and 18 are arcuate in configuration, and that the contactor 16 will be in contact with either of the contacts 17 and 18.

By means of this arrangement the coil 14 functions as a short-circuited winding with respect to coil 3, as long as contactor 16 is in contact with element 17. When the contactor 16 is adjusted into contact with element 18 then the short-circuiting effect of coil 14 is eliminated, and coil 15 10 comes under the influence of the short-circuiting coil 15. The effective inductances of coils 3 and 7 are chosen so that circuits 2 and 5 "track" when contactor 16 is adjusted to the maximum selectivity position; that is to say 20 when the contactor 16 is in contact with element 17. In Fig. 2 the curve designated as "Selectivity" denotes the overall resonance curve characteristic of pre-selector circuits 2 and 5 when contactor 16 is adjusted to contact element 17. 25 It will be observed that in this position of the contactor the effect of the short-circuiting coil 14 is to decrease the inductance in circuit 2, with respect to its normal non-short circuited state, and thus increase the resonant frequency of the 30 circuit at the particular setting of the variable condenser 4.

When the contactor 16 is adjusted to contact element 18, the short-circuiting effect of coil 14 is removed, and the resonance curve characteristic of circuit 2 is denoted by the curve *a* 35 in Fig. 2. It will be seen that the resonant frequency of circuit 2 has been shifted from F_0 which is the maximum selectivity frequency, to a lower frequency F_a . Simultaneously the short- 40 circuiting coil 15 functions to decrease the effective inductance in pre-selector circuit 5, and this causes the resonant frequency of the circuit to increase to a value F_b . The resonance curve characteristic *b* in Fig. 2 illustrates the effect on 45 the characteristic of circuit 5 when coil 15 is made electrically effective. The overall resonance curve designated "Fidelity" illustrates how the pre-selector band characteristic has been spread by adjusting contactor 16 into contact 50 with element 18.

The band width control device 13 and the contactor 16, if desired, may be mechanically coupled in the manner designated by the dotted line 21 in order to provide a predetermined relation between the adjustment of device 13 and contactor 16. For example, the adjustment may be such that the fidelity adjustment of contactor 16 is not had until the device 13 has been adjusted through a predetermined portion of its 60 control range. It is desirable for smooth tuning characteristics (no whistles, etc.), to have good pre-selector selectivity. Only when the IF amplifier, which is usually much more selective than the radio frequency circuit, is very broad does 65 the radio selectivity contribute an appreciable percent of the total high frequency attenuation. When the IF amplifier is broad, or control 21 well advanced, then radio selectivity should be sacrificed to add the last contribution to fidelity. 70 Hence, the switch-over of 16 contacting 18 should occur at an advanced position. On the other hand, the contactor 16 may be employed independently of device 13. It will be noted that when the contactor 16 is in contact with element 75

17 the pre-selector circuits 2 and 5 are brought into resonance with each other, and hence the gain of the stages including these circuits is materially increased. It is to be understood that 5 the short-circuited coil can be coupled to the second radio frequency circuit, and the open-circuited coil coupled to the first radio frequency circuit, in the selective position of contactor 16.

While I have indicated and described one system for carrying my invention into effect, it will be apparent to one skilled in the art that my invention is by no means limited to the particular organization shown and described, but that many modifications may be made without 15 departing from the scope of my invention as set forth in the appended claims.

What I claim is:

1. In combination with a pair of cascaded resonant circuits, each resonant circuit including 20 a coil and tuning condenser arranged in shunt relation, an auxiliary coil disposed in coupled relation to the coil of one of said circuits, a second auxiliary coil disposed in coupled relation to the coil of said second of said resonant 25 circuits, means for selectively rendering either of said auxiliary coils effective as a short-circuiting winding with respect to its associated coil, one of said auxiliary coils having a magnitude such that said pair of circuits are tuned to a 30 common frequency when said one coil acts as a short-circuiting winding, and the other auxiliary coil having a magnitude such that said circuits are each detuned from the frequency when it acts as short-circuiting winding.
- 35 2. In combination with a pair of cascaded resonant circuits, said circuits being tuned substantially to a common carrier frequency, each resonant circuit including a coil and tuning condenser arranged in shunt relation, an auxiliary 40 coil disposed in coupled relation to the coil of one of said circuits, a second auxiliary coil disposed in coupled relation to the coil of said second of said resonant circuits, means for selectively rendering either of said auxiliary coils effective as a short-circuiting winding with 45 respect to its associated coil, each of said auxiliary coils having a terminal connected to a contact, the opposite terminals of the auxiliary coils being grounded, and said means including a 50 grounded contactor adapted to be connected to either of said contacts.
- 55 3. In a radio receiver which includes at least two tunable signal circuits arranged in cascade, each of said signal circuits including a coil and a tuning condenser, the second of said signal 60 circuits being tuned to a desired signal frequency, an auxiliary circuit reactively coupled to said first signal circuit to a sufficient extent substantially to change the frequency thereof and including an adjustable element for selectively opening or closing the auxiliary circuit, and said first signal circuit being effectively tuned to said desired signal frequency when said adjustable element is in position solely to close the auxiliary circuit.
- 65 4. In a radio receiver which includes at least

two tunable signal circuits arranged in cascade, each of said signal circuits including a coil and a tuning condenser, the second of said signal circuits being tuned to a desired signal frequency, an auxiliary circuit reactively coupled to said first signal circuit to a sufficient extent substantially to change the frequency thereof and including an adjustable element for selectively opening or closing the auxiliary circuit, said first signal circuit being effectively tuned to said desired signal frequency when said adjustable element is in position solely to close the auxiliary circuit, and a second auxiliary circuit reactively coupled to said second signal circuit, and including said adjustable element to control 15 the effect of said second auxiliary circuit on the resonant frequency of said second signal circuit.

5. In a radio receiver which includes at least two tunable signal circuits arranged in cascade, 20 each of said signal circuits including a coil and a tuning condenser, the second of said signal circuits being tuned to a desired signal frequency, an auxiliary circuit reactively coupled to said first signal circuit to a sufficient extent 25 substantially to change the frequency thereof and including an adjustable element for selectively opening or closing the auxiliary circuit, said first signal circuit being effectively tuned to said desired signal frequency when said adjustable 30 element is in position solely to close the auxiliary circuit, a second auxiliary circuit reactively coupled to said second signal circuit, and including said adjustable element to control the effect of said second auxiliary circuit on the 35 resonant frequency of said second signal circuit, and the frequencies of said two signal circuits being positively detuned from said desired signal frequency by equal frequency values, when the adjustable element is adjusted to open the first 40 auxiliary circuit and close the second auxiliary circuit.

6. In a radio receiver having at least three cascaded resonant circuits, means for varying the selectivity of the third of the circuits, means 45 electrically coupled with the first two circuits for varying the selectivity thereof as a unit, and additional means for adjusting said two means in the same sense but in successive relation such that said second selectivity varying means is 50 adjustable over solely a portion of the first varying means range.

7. In a radio receiver having at least three cascaded resonant circuits, means for varying the selectivity of the third of the circuits, means 55 electrically coupled with the first two circuits for varying the selectivity thereof as a unit, and additional means for adjusting said two means in the same sense but in successive relation such that said second selectivity varying means is 60 adjustable over solely a portion of the first varying means range, the second varying means comprising a device for controlling the tuning of said first two circuits with respect to a common carrier frequency.

GARRARD MOUNTJOY.
